UNITED STATES PATENT OFFICE.

MAXIMILLIAN P. JANISCH, OF MUSKEGON, MICHIGAN.

ALARM.

SPECIFICATION forming part of Letters Patent No. 699,531, dated May 6, 1902.

Application filed January 2, 1902. Serial No. 88,148. (No model.)

To all whom it may concern:

Be it known that I, MAXIMILLIAN P. JANISCH, a citizen of the United States, and a resident of Muskegon, in the county of Muskegon and State of Michigan, have invented certain new and useful Improvements in Alarms; and I do hereby declare that the following is a full, clear, and exact description thereof.

The improvements consist in what is hereinafter particularly set forth with reference to the accompanying drawings and subsequently claimed, the main object of the invention being to provide an alarm-controller adjustable to be brought into the opening path of an ordinary hinge-hung door, whereby pressure of the door on said controller will result in a protracted alarm.

A further object of the invention is to provide for yield of the carrier of the alarm-controller to clear the door in case the latter is opened far enough to permit a person to cross the threshold of its frame.

A still further object of the invention is to provide for operating the alarm-controller from outside the door when said controller and its carrier are adjusted out of the opening path of said door.

Figure 1 of the drawings represents an elevation in full lines of a mechanical alarm mechanism partly broken and adjustable on a door-frame to be out of the opening path of the adjacent door, a dotted-line diagram of said mechanism being shown in the same figure opposing the door; Fig. 2, a sectional view indicated by line 2 2 in the first figure; Fig. 3, a similar view indicated by line 3 3 in the second figure; and Fig. 4, a detail plan view, partly in horizontal section, illustrating a push-stem and gravity-latch for same embodied in the alarm mechanism herein illustrated.

Referring by letter to the drawings, A indicates a vertical portion of a door-frame, and B a portion of the door, that in practice is hinged to the frame to be swung inward. Fastened to said vertical portion of the door-frame by screws or otherwise is a disk C, having an annular flange b and radial lugs c d e, these lugs being at quarter-intervals of a circle. The disk flange engages the space within an annular flange f of an arm D, and the same space contains a spiral spring E, normally contracted by means of a pivot-screw F, that

extends through arm and disk apertures into the adjacent door-frame. The head of the screw is made to have frictional contact with arm D, and spring E serves to compensate for lost motion in the pivot-joint of said arm and fixture on the door-frame. A lateral fin g of arm D is arranged to play between disk lugs d c or d e, accordingly as the door is hung to open right or left, said lugs serving as stops to limit adjustment of said arm and parts in connection therewith.

Upper ears h of arm D are connected to ears i of a ring G by means of a pivot j, and a spiral spring k is arranged on the pivot to normally hold the ring in the same plane as said arm, the joint being a flexible one for the purpose hereinafter specified. Fast on inner radial ears of ring G is the frame of a common type of spring-motor having a gong-bell H in screw-thread connection with the mainspring-arbor, said spring being wound by turning the bell in the proper direction. The rod-shank m of the bell-striker is in connection with the axis of the pallets that engage with the escapement-wheel J of the motor, and a collar n of a push-stem K is normally in contact with said shank under the same to check operation of said motor, there being protracted ringing of the bell when said collar is clear of said shank. The push-stem is retractive in the motor-frame against resistance of a spiral spring p, arranged on said stem between its collar and a plate of said frame. The outer end of the push-stem is provided with a head q, and an annular groove r is formed in said stem adjacent to its inner end.

In pivotal connection with the motor-frame is a gravity-latch L, having upper corner-lugs s, of which one or the other thereof is engageable with the annular groove in push-stem K when arm D and parts in connection therewith are swung down from vertical or horizontal position in the opening path of the door aforesaid. The gravity-latch is preferably provided with an upper central and offset lug t, that constitutes a stop for the push-stem when said latch is vertical.

The shank u of a spring-controlled push-button M is shown extended through the door-frame to operate against head q of push-stem K when the same is in register there-

with, whereby the alarm mechanism may be operated from outside the door and serve the purpose of an ordinary door-bell.

While I have shown and described an automatic mechanical alarm mechanism of which the spring-controlled push-stem K is the controller, it is practical to substitute an electric or other variety of automatic alarm mechanism operative incidental to pressure exerted on its controller, the latter having a pivotal carrier that is preferably in two sections having spring-controlled flexible union. The door being closed and the alarm-controller carrier swung from vertical to horizontal position, the gravity-latch L automatically adjusts itself to have a lug s thereof abut said alarm-controller ready to engage the groove r of same, as shown by dotted lines in Fig. 1 and full lines in Fig. 4. Now if the door be unlatched and pushed ajar there will be engagement of the alarm-controller with the gravity-latch, and a protracted alarm will result. Owing to the flexible joint of the alarm-controller carrier the door may be swung far enough open to permit a person to cross the threshold of its frame without damaging said carrier, the latter yielding sufficiently to clear said door, it being understood that the adjustment of said carrier may be otherwise than pivotal without departure from the generic scope of my invention.

Having thus described my invention, what I claim as new, and desire to secure by Letters Patent, is—

- 35 1. An automatic alarm-controller and a carrier with which it has retractive engagement adjustable to be in or out of the opening path of a door, and a latch automatically engageable with said controller on retraction of the same by door-pressure thereon.
2. An automatic alarm-controller and a pivotally-adjustable flexibly-jointed carrier with which it has retractive engagement, and a latch automatically engageable with the controller to hold the same in retracted position subsequent to pressure thereon when said carrier is arranged and adjusted in connection with a support to be in the opening path of a door.
- 45 3. An automatic alarm-controller and carrier for same adjustable in connection with a support to be in or out of the opening path of a door, and an independent spring-controlled push-button arranged in connection with the door-frame to have its shank oppose said controller when the same with its carrier is adjusted out of said opening path of the door.
4. A door-frame fixture having an annular flange and radial lugs, an arm having a flange lapping the fixture-flange and provided with a fin having play between fixture-lugs, a pivot extending through the arm and fixture, a spiral spring surrounding the pivot under

compression, between said arm and fixture, a spring-motor adjustable with the aforesaid arm, a gong-bell in connection with the main-spring-arbor of the motor, a bell-striker having shank connection with the pallet-axis of said motor, and a spring-controlled push-stem having a collar arranged to be normally under the bell-striker shank to check operation of the aforesaid motor.

5. A door-frame fixture having an annular flange and radial lugs, an arm having a flange lapping the fixture-flange and provided with a fin having play between fixture-lugs, a pivot extending through the arm and fixture, a spiral spring surrounding the pivot under compression between said arm and fixture, a spring-motor adjustable with the aforesaid arm, a gong-bell in connection with the main-spring-arbor of the motor, a bell-striker having shank connection with the pallet-axis of the motor, a spring-controlled push-stem having a collar arranged to be normally under the bell-striker shank to check operation of said motor, and a gravity-latch automatically adjustable to be engageable with the push-stem when the latter is retracted by pressure of a door subsequent to having been brought in the opening path of same.

6. A door-frame fixture, a flexibly-jointed carrier in pivotally-adjustable connection with the fixture, automatic alarm mechanism in connection with the carrier, and an alarm-controller in the form of a push-stem arranged to be brought with said carrier in the opening path of a door.

7. A door-frame fixture, a flexibly-jointed carrier in pivotally-adjustable connection with the fixture, automatic alarm mechanism in connection with the carrier, an alarm-controller in the form of a push-stem arranged to be brought with said carrier into the opening path of a door, and means for holding said push-stem in retracted position subsequent to door-pressure thereon.

8. A carrier for adjustable connection with a door-frame automatic alarm mechanism in connection with the carrier, an alarm-controller in the form of a spring-controlled push-stem arranged to be brought with said carrier in the opening path of a door, and a spring-controlled push-button for connection with the door-frame to have its shank in register with said push-stem when the latter and the aforesaid carrier are adjusted out of the way of the door.

In testimony that I claim the foregoing I have hereunto set my hand, at Muskegon, in the county of Muskegon and State of Michigan, in the presence of two witnesses.

MAXIMILLIAN P. JANISCH.
